His attorney.

UNITED STATES PATENT OFFICE.

REGINALD FRANCIS HALLIWELL, OF RUGBY, ENGLAND, ASSIGNOR TO GENERAL ELECTRIC COMPANY, A CORPORATION OF NEW YORK.

VALVE MECHANISM FOR ELASTIC-FLUID TURBINES OR OTHER PRIME MOVERS.

Application filed May 10, 1921. Serial No. 463,399.

To all whom it may concern:

Be it known that I, REGINALD FRANCIS HALLIWELL, a subject of the King of Great Britain, residing at Rugby, in the county of 5 Warwickshire, England, have invented certain new and useful Improvements in Valve Mechanisms for Elastic-Fluid Turbines or Other Prime Movers, of which the following is a specification.

10 This application is a continuation in part of my application Ser. No. 362,281, filed March 1, 1920.

The present invention relates to valve mechanisms for controlling the supply of 15 elastic fluid to turbines or other prime movers which are supplied with elastic fluid from two sources of different pressures. One application of my invention is in connection with elastic fluid turbines of the 20 so-called mixed pressure type wherein the turbine is supplied with higher pressure elastic fluid and also with elastic fluid of lower pressure, which latter may be elastic fluid exhausting from non-condensing engines 25 for example. With any such arrangement, it is desirable that the turbine or other prime mover be operated as far as possible by the lower pressure fluid, the higher pressure fluid being utilized to supplement the 30 lower pressure fluid, since this leads to the greatest economy in operation.

The object of my invention is to provide an improved valve mechanism of the above referred to type, and for a consideration of 35 what I believe to be novel and my invention, attention is directed to the accompanying description and the claims appended thereto.

In the course of the following specification 40 the invention is particularly described as applied to a mixed pressure turbine but it will be understood that the invention is not necessarily limited to turbines but may be used in connection with other forms of 45 prime movers.

In the drawing, Fig. 1 is a diagrammatic view of a valve mechanism embodying my invention, only so much of the turbine being shown as is necessary to an understanding 50 of the operation of the valve mechanism, and Fig. 2 is a detail view of part of the high pressure valve means.

Referring to the drawing, 5 indicates the high pressure elastic fluid valve chest of the

turbine in which are arranged a number of 55 valves which have their stems 6 connected to operating levers 7, which levers are successively raised to open the valves by a cam-shaft 8 which is turned by a suitable servomotor. In the present instance, such servomotor is shown as comprising an annular 60 cylinder 9 in which moves a piston in the form of a blade or plate 10. Cylinder 9 is divided by partition member 11 and actuating fluid for moving blade 10 is admitted 65 on opposite sides of partition member 11 through pipes 12 and 13. The high pressure valve gear and actuating means therefor just described is of known type and is 70 to be taken as typical of any suitable type of valve gear.

Low pressure elastic fluid is admitted to the turbine through a valve 14, the elastic fluid entering through inlet 15 and being discharged to the turbine through outlet 75 16. The stem 17 of valve 14 is connected by means of a cross head 18 to the central portion of a lever 19. One end of lever 19 is pivoted on a nut 20 which threads on the upper end of a rod 21, and the other end is 80 pivotally connected through a link 22 to the stem 23 of a fluid-actuated motor comprising piston 24 and cylinder 25. The lower end of rod 21 passes through a guide 26 and carries at its end a spring holder 27 85 between which and guide 26 is arranged a spring 28 which acts in a direction to close valve 14. Rod 21 is normally held in the position shown in the drawing by a trip trigger 29 which engages a notch in it. Trip trigger 29 is connected in any suitable manner to either a hand lever, an emergency 90 governor for the turbine, or both, and the arrangement is such that whenever the trip trigger is actuated, stem 21 will be released 95 and valve 14 will be automatically closed by spring 28. Connected to nut 20 is a hand wheel 30 and, by turning the hand wheel, valve 14 can be closed and opened 100 manually as is obvious.

Fluid motor cylinders 9 and 25 are connected in parallel to a common pilot valve 31, the cylinder 9 being connected thereto by pipes 12 and 13 and the cylinder 25 being connected thereto by pipe 32 and pipe sections 33 and 33^a. Pipes 12 and 32 both connect to port 34 of the pilot valve and pipes 13 and 33 both connect to port 35. Ports

34 and 35 are controlled by spaced valve members 36 and 37 carried by pilot valve stem 38, and operating fluid is admitted to the space between valve members 36 and 37 by a pipe 39. Any suitable operating fluid for the servo-motors may be employed but preferably I connect pipe 39 to the forced feed lubricating system of the turbine and utilize oil as the operating fluid. The discharge pipe from the pilot valve is indicated at 40. Pilot valve stem 38 is connected to the central portion of a floating lever 41, one end of which is connected to the governor lever 42 of a suitable speed governor 43. Governor 43 may be taken as typical of any suitable type of speed governor and its spindle 44 is driven from the turbine shaft in the usual manner as will be understood. The other end of floating lever 41 is connected by a link 45 to one end of a lever 46, the other end of which is connected to stem 17 of valve 14. At an intermediate point, lever 46 is connected by a link 47 to a rack 48 which engages with a pinion 49 on cam shaft 8.

The fluid-actuated motor comprising cylinder 25 and piston 24 in addition to being under the control of pilot valve 31, which is speed governor actuated, is also under control of a pressure actuated abutment here shown in the form of a piston 50 which moves in a cylinder 51. Connected to piston 50 is a stem 52, the outer end of which is connected by a link 53 to one end of a lever 54, the other end of which is connected to stem 17 of valve 14. Surrounding stem 52 is an adjustable spring 55 which acts to bias piston 50 toward the top of cylinder 51. Spring 55 is located between the top wall of cylinder 51 and an adjustable collar 55^a on stem 52. The cylinder space above piston 50 is connected by a pipe 56 to the casing of valve 14 so that the upper side of piston 50 is subjected to the pressure of the low pressure fluid supply. The cylinder space below piston 50 is connected by a pipe 57 to any suitable point of constant pressure, such as for example, to atmosphere, or in cases where it is desired to regulate the opening of the low pressure valve 14 by the vacuum, pipe 57 may be there connected to the condenser. Interposed between pipe sections 33 and 33^a is a valve casing 58 having a chamber 58^a in which are two spaced valves 59 and 59^a carried by a valve stem 59^b which is connected by a link 59^c to lever 54 at a point which is distant from the ends of lever 54 approximately in proportion to the amounts of travel of stem 17 and piston 50. Pipe 33 is connected to chamber 58^a through a port 60 located between valves 59 and 59^a and pipe 33^a is connected to chamber 58^a through a port 60^a adapted to be just covered by valve 59. Valve 59^a covers a port 60^b in casing 58 and is made longer than valve 59

so that a downward movement of valves uncovers port 60^a before port 60^b and port 60^b is not uncovered by an upward movement of the valves. The ends of chamber 58^a beyond valves 59 and 59^a are connected by a passage 61 and leading from the lower end of casing 58 is a discharge pipe 63 which connects with discharge pipe 40. Valves 59 and 59^a are moved by piston 50 and it will be noted that the arrangement is such that when piston 50 is held down by the pressure of the low pressure elastic fluid in its lowermost position against the action of spring 55, port 60 is connected to port 60^a so pipes 33 and 33^a are connected together, and port 60^b is connected through passage 61 to discharge pipe 63. Valve 59^a then lies below port 60^b but valve 59 does not descend far enough to cover the lower end of passage 61 so that its connection to discharge pipe 63 is maintained. When valves 59 and 59^a are in their central position valve 59 covers the port 60^a so port 60^a is disconnected from port 60 and valve 59^a covers port 60^b. When valves 59 and 59^a are in their uppermost position valve 59 opens port 60^a and places pipe 33^a in communication with discharge pipe 63, port 60^b still being covered by valve 59^a.

In discharge pipe 40 is an adjustable spring-pressed relief valve 64 which serves to maintain in the portion of pipe 40 in advance of it a certain desired intermediate pressure. Connecting inlet pipe 39 to pipe 40 is a by-pass 65 in which is a pressure relief valve 66 for relieving excess pressure in inlet pipe 39.

As is clear from the foregoing description, speed governor 43 controls both the high pressure valve means and the low pressure valve means through pilot valve 31 to which they are connected in multiple, and in order to insure that the low pressure valve means open prior to the high pressure valve means and closes subsequently thereto, I provide a means whereby the fluid pressure required to actuate the low pressure valve means is less than that required to actuate the high pressure valve means. To this end I may arrange the fluid motors themselves so that more pressure is required to operate the one controlling the high pressure valve means than is required to operate the one controlling the low pressure valve means, or I may utilize other suitable means to accomplish this result. In the present instance, I have shown the pipes 13 and 33 which lead from the pilot valve 31 to cylinders 9 and 25 respectively as provided with valve means 67 and 68 which permit of practically unrestricted flow of fluid in one direction but offer a resistance to flow of fluid in the other direction. These valve means are shown as being alike and each comprises a piston 67^a or 68^a which slides

freely in the valve means casing and through which is an opening controlled by an adjustable spring pressed valve 67^b or 68^b. In the case of valve means 67 fluid flowing through pipe 13 toward cylinder 9 must pass through valve 67^b and hence must overcome the pressure of its spring while fluid flowing in the opposite direction, i. e., away from cylinder 9, can raise piston 67^a and thus have unrestricted flow. In the case of valve means 68 the arrangement is such that fluid may flow freely through pipe 33 toward cylinder 25 but must overcome the resistance of spring-pressed valve 68^b in order to flow in the reverse direction.

At a point between cylinder 9 and valve means 67, pipe 13 is connected by a pipe 70 to port 60^b in valve casing 58. In the present instance the connection to pipe 13 is made through the bottom of the casing of valve means 67.

The operation is as follows:—Assume the turbine is in operation and that there is a supply of low pressure elastic fluid being supplied through valve 14 of such pressure as to hold piston 50 down in cylinder 51 against the action of spring 55. Under these circumstances valve 59 lies below port 60^a but is not low enough to cover the lower end of passage 61. Port 60^a is thus connected directly to port 60 placing the lower end of cylinder 25 in direct communication with pipe 33. Pilot valve 31, and hence governor 43 is then in direct control of both the high pressure valve means and the low pressure valve means. However, due to valve means 67 and 68 in pipes 13 and 33 respectively, it will be clear that the low pressure valve means will be fully opened prior to the opening of the high pressure valve means and will close subsequently thereto. If the load increases, thus lowering the turbine's speed, governor 43 will act to raise the stem 38 and valves 36 and 37 of pilot valve 31 thereby connecting pilot valve port 35 to inlet pipe 39 and pilot valve port 34 to discharge pipe 40. Operating fluid from pipes 39 will then pass to pipes 13 and 33. In the case of the pipe 13 the pressure of the fluid must overcome the spring pressure of valve 67^b before it can enter the cylinder 9 of the servo-motor for the high pressure valve means. In the case of pipe 33, however, piston 68^a affords practically no resistance to the flow of fluid and hence will permit the flow of fluid directly to the lower end of cylinder 25, thus acting to raise piston 24 to open further the low pressure valve 14. If, however, the low pressure valve is fully open, then the pressure in pipes 13 and 33 will build up sufficiently high to overcome the spring controlled valve 67^b thus admitting operating fluid to cylinder 9, which results in the plate-like piston 10 therein being moved in an anti-clockwise direction to open

one or more of the valves of the high pressure valve means. In the case of a movement of the low pressure valve means or of the high pressure valve means, lever 46 is moved by stem 17 or by rack 48 and pinion 49 to restore the pilot valve 31 to its original position, the action being that of the well understood follow-up device. In case of a decrease in load, thus permitting the turbine's speed to increase, an action similar to that already described takes place except in the opposite sense, the high pressure valve means being first closed, followed by closing of the low-pressure valve means. This is due to the fact that operating fluid can escape freely from cylinder 9 past valve 67 to pilot valve 31 but can escape from the under side of piston 24 back to pilot valve 31 only by overcoming the pressure of the spring-controlled valve 68^b.

In case of failure in the supply of low pressure elastic fluid to valve 14, the pressure above piston 50 in cylinder 51 will be relieved and spring 55 will raise piston 50 thereby lifting valves 59 and 59^a in cylinder 58 and placing pipe 33^a in communication with discharge pipe 63. Due to the presence of the spring-pressed relief valve 64 in pipe 40, an intermediate pressure is always maintained in pipes 12 and 32 equal to that for which relief valve 64 is set. This pressure acting on the top of piston 24 serves to quickly force it downward when the pressure beneath it is relieved as just described, such action taking place entirely independent of pilot valve 31. When the low pressure valve 14 closes, the left hand end of lever 46 is lowered and the right hand end raised, the same fulcruming about the end of link 47. As a result pilot valve 31 is raised to admit the full pressure of the actuating fluid from pipe 39 to pipe 13 with the result that servomotor 9 is immediately operated to open the high pressure valve means. High pressure elastic fluid is thereupon immediately supplied in lieu of the low pressure elastic fluid upon which the turbine had previously been operating. When the high pressure valve means is thus operated, pilot valve 31 is restored to its original position by means of pinion 49 and rack 48 as already referred to. The connections of the lever 46 to low pressure valve 14, floating lever 41 and rack 48 are so proportioned that when the low pressure valve means closes, the high pressure valve means will be opened to an extent to supply just sufficient elastic fluid to maintain the speed of the turbine. As a result, in changing from low pressure operation to high pressure operation or vice-versa, speed governor 43 is not affected.

If, now, the supply of low pressure elastic fluid is restored, then piston 50 will be lowered in cylinder 51 thereby lowering the valves 59 and 59^a and connecting port 60^a to

port 60. As soon as port 60 is connected to port 60^a actuating fluid flows through pipes 33 and 33^a to the lower end of cylinder 25 to quickly raise piston 24 and open low pressure valve 14. When piston 24 rises the fluid above it is forced out through pipes 32 and 12 directly to servo-motor 9 entering on the lower side of blade 10. At the same time the servo-motor on the upper side of blade 10 is connected by way of the section of pipe 13 which lies between cylinder 9 and valve means 67, pipe 70, port 60^b and passage 61 to discharge pipe 63. As a result, the fluid forced from piston 25 acts on blade 10 to move it in a direction to close the high pressure valve or valves 5. It will thus be seen that when the supply of lower pressure elastic fluid is restored, low pressure valve 14 is opened and high pressure valve means 5 is closed at the same time and independently of the speed governor 43.

In accordance with the provisions of the patent statutes, I have described the principle of operation of my invention, together with the apparatus which I now consider to represent the best embodiment thereof, but I desire to have it understood that the apparatus shown is only illustrative and the invention may be carried out by other means.

What I claim as new and desire to secure by Letters Patent of the United States, is,—

1. In combination, a plurality of valve means for admitting elastic fluid of different pressures to a machine, a fluid actuated motor for each valve means, a single pilot valve connected to said motors in multiple, a governor connected to said pilot valve, means which effects the operation of said motors in sequence, a movable abutment which is subjected to the pressure of the elastic fluid supplied through one of said valve means, and means connecting such movable abutment to such valve means.

2. The combination with a machine, of a valve means for supplying high pressure elastic fluid thereto, a valve means for supplying low pressure elastic fluid thereto, a fluid actuated motor for each valve means, a single pilot valve connected to said motors in multiple, a governor connected to said pilot valve, a movable abutment which is subjected to the pressure of the low pressure elastic fluid, and means whereby it may take control of the fluid actuated motor for the low pressure valve means to the exclusion of the governor.

3. The combination with a machine, of a valve means for supplying high pressure elastic fluid thereto, a valve means for supplying low pressure elastic fluid thereto, a fluid actuated motor for each valve means, a single pilot valve connected to said motors in multiple, a governor connected to said pilot valve, a movable abutment which is

subjected to the pressure of the low pressure elastic fluid, means controlled by said movable abutment for closing the low pressure valve means in case the supply of low pressure elastic fluid fails, and means connecting a moving part of the low pressure valve means to said pilot valve whereby when the low pressure valve closes the pilot valve will be actuated to effect an opening movement of said high pressure valve means.

4. The combination with a machine, of a valve means for supplying high pressure elastic fluid thereto, a valve means for supplying low pressure elastic fluid thereto, a fluid actuated motor for each valve means, a pilot valve, conduits connecting said pilot valve to both said fluid actuated motors, means associated with said conduits which offer resistances of different degrees to the flow of fluid therethrough, whereby said valve means are operated in sequence, a movable abutment which is subjected to the pressure of the low pressure elastic fluid, and means controlled by said abutment for disconnecting the fluid motor for the low pressure valve means from said pilot valve and permitting such motor to close the low pressure valve means.

5. The combination with a machine, of a valve means for supplying high pressure elastic fluid thereto, a valve means for supplying low pressure elastic fluid thereto, a fluid actuated motor for each valve means, a pilot valve, conduits connecting said pilot valve to both said fluid actuated motors, means associated with said conduits which offer resistances of different degrees to the flow of fluid therethrough, whereby said valve means are operated in sequence, a movable abutment which is subjected to the pressure of the low pressure elastic fluid, means controlled by said abutment for disconnecting the fluid motor for the low pressure valve means from said pilot valve and permitting such motor to close the low pressure valve means, and means including a follow-up device connecting the low pressure and high pressure valve means to said pilot valve whereby when the low pressure valve means closes, the pilot valve will be operated to effect an opening movement of the high pressure valve means.

6. The combination with a machine, of a valve means for supplying high pressure elastic fluid thereto, a valve means for supplying low pressure elastic fluid thereto, a fluid actuated motor for each valve means, a pilot valve, conduits connecting said pilot valve to both said fluid actuated motors, valve mechanism in one of the conduits connecting the pilot valve to the motor of the low pressure valve means which is adapted to interrupt the flow of actuating fluid from the pilot valve through such conduit and connect the motor to a region of lower pres-

sure, and means controlled by the pressure of the low pressure elastic fluid for actuating said valve mechanism.

7. The combination with a machine, of a valve means for supplying high pressure elastic fluid thereto, a valve means for supplying low pressure elastic fluid thereto, a fluid actuated motor for each valve means, a pilot valve, conduits connecting said pilot valve to both said fluid actuated motors, a discharge pipe for the pilot valve, a check valve therein whereby an intermediate pressure is maintained in said conduits, valve mechanism in one of the conduits connecting the pilot valve to the motor of the low pressure valve means which is adapted to interrupt the flow of actuating fluid from the pilot valve through such conduit and connect the motor to a region of lower pressure, and means controlled by the pressure of the low pressure elastic fluid for actuating said valve mechanism. 70

8. The combination with a machine, of a valve means for supplying high pressure elastic fluid thereto, a valve means for supplying low pressure elastic fluid thereto, a fluid actuated motor for each valve means, a pilot valve, conduits connecting said pilot valve to both said fluid actuated motors, a governor connected to said pilot valve, valve mechanism in one of the conduits connecting the pilot valve to the motor of the low pressure valve means which is adapted to interrupt the flow of actuating fluid from the pilot valve through such conduit and connect the motor to a region of lower pressure, whereby the motor may operate to close the low pressure valve means, and means including a follow-up device connecting the low pressure valve means and the high pressure valve means to said pilot valve whereby when the low pressure valve means move toward closed position the pilot valve will be actuated to effect an opening movement of the high pressure valve means. 95

9. The combination with a machine, of a valve means for supplying elastic fluid thereto, a motor for actuating it, a pilot valve, conduits connecting the pilot valve to the motor, a discharge pipe for the pilot valve, a check valve therein which serves to maintain an intermediate pressure in said conduits, a valve mechanism in one of said conduits adapted to disconnect such conduit from said pilot valve and connect a side of the motor to a region of lower pressure, and means for actuating said valve mechanism. 110

10. The combination with a machine, of a valve means for supplying elastic fluid thereto, a motor for actuating it, a pilot valve, conduits connecting the pilot valve to the motor, a discharge pipe for the pilot valve, a check valve thereon which serves to maintain an intermediate pressure in said conduits, a valve mechanism in one of said

conduits adapted to disconnect such conduit from said pilot valve and connect a side of the motor to a region of lower pressure, and means controlled by the pressure of the elastic fluid supplied through said valve means for actuating said valve mechanism. 130

11. The combination with a machine, of a valve means for supplying high pressure elastic fluid thereto, valve means for supplying low pressure elastic fluid thereto, a fluid actuated motor for each valve means, a pilot valve, conduits connecting said pilot valve to both said fluid actuated motors, means associated with said conduits which offer resistances of different degrees to the flow of fluid therethrough, whereby said valve means are operated in sequence, a movable abutment which is subjected to the pressure of the low pressure elastic fluid, means controlled by said abutment for disconnecting the fluid motor for the low pressure valve means from said pilot valve and permitting such motor to close the low pressure valve means, and means whereby when said abutment is moved to again connect the fluid motor for the low pressure valve means to said pilot valve, a side of such fluid motor is connected to the fluid motor for the high pressure valve means to effect a closing movement of the high pressure valve means. 145

12. The combination with a machine, of a valve means for supplying high pressure elastic fluid thereto, a valve means for supplying low pressure elastic fluid thereto, a speed governor and fluid motors for regulating both said valve means, and means responsive to the pressure of the low pressure elastic fluid and operating independently of the speed governor for effecting a closing of the low pressure valve means and an opening of the high pressure valve means when the supply of low pressure elastic fluid fails and for effecting an opening movement of the low pressure valve means and a closing movement of the high pressure valve means when the supply of low pressure elastic fluid is restored, said high pressure valve means being closed by fluid discharged from the fluid motor for the low pressure valve means. 160

13. A regulating system for a mixed pressure turbine comprising a valve means controlling the admission of high pressure elastic fluid, a valve means for controlling the admission of low pressure elastic fluid, fluid motors for said valve means, a speed governor controlling both said valve means through the medium of said fluid motors, and a means responsive to the pressure of the low pressure elastic fluid for controlling both said valve means also, characterized by the fact that when the supply of low pressure elastic fluid is restored after having failed, the fluid motor for the high pressure valve means is operated by fluid 175

discharged from the fluid motor for the low pressure valve means to effect a closing movement of the high pressure valve means.

14. The combination with a machine, of a valve means for supplying high pressure elastic fluid thereto, a valve means for supplying low pressure elastic fluid thereto, a fluid actuated motor for each valve means, a single pilot valve controlling both said motors, a governor connected to said pilot valve, a movable abutment which is subjected to the pressure of the low pressure elastic fluid, means controlled by said movable abutment for closing the low pressure valve means in case the supply of low pressure elastic fluid fails, means connecting a moving part of the low pressure valve means to said pilot valve whereby when the low pressure valve closes the pilot valve will be actuated to effect an opening movement of said high pressure valve means, and means whereby when the supply of low pressure elastic fluid is restored the fluid motor for the high pressure valve means will be actuated by fluid discharged from the fluid motor for the low pressure valve means to effect a closing movement of the high pressure valve means.

15. In a governor mechanism for a mixed-pressure elastic-fluid prime-mover, the combination with motor operated high-pressure and low pressure throttle valves of a single pilot valve controlling said throttle valves, an elastic fluid pressure actuated means, means connecting the pressure actuated means to the low pressure throttle valve for operating said throttle valve independently of the pilot valve, means connecting the low pressure throttle valve with the pilot valve whereby a movement of the former causes the pilot valve to operate the high pressure throttle valve and maintain the supply of elastic fluid constant to the prime mover and means associated with the pilot valve for giving the throttle valves proper sequence of operation during changes in load.

16. In a governor mechanism for an elastic-fluid prime mover, the combination of a

speed governor, a single pilot valve controlled by said governor, throttle valves for the elastic fluid controlled by said pilot valve, a pressure governor controlled by elastic fluid pressure, a valve controlled by said governor, said valve forming an intermediary control between the pilot valve and one of said throttle valves, whereby a change in the pressure of the elastic fluid supplied through said last named throttle valve will change the position of said throttle valve relative to its closed position, means connecting said throttle valve with the pilot valve whereby upon the closing of said throttle valve the pilot valve will be moved to open another throttle valve to keep the supply of elastic fluid to the prime mover constant and means associated with the pilot valve for operating the throttle valves in proper sequence.

17. In a governor mechanism for a mixed-pressure elastic-fluid prime-mover the combination of a speed governor comprising a centrifugal governor, a pilot valve connected therewith, throttle valves for elastic fluid control, a motor for each throttle valve connected with said pilot valve, a pressure governor comprising a movable abutment subjected to the pressure of one source of elastic fluid supply, a cut-off valve connected therewith, said cut-off valve controlling a throttle valve motor independently of the pilot valve, means in the pilot valve connections for operating the throttle valves in proper sequence, and means connecting the speed governor with the pressure governor whereby the speed governor may assume complete control of the governor mechanism during load changes and the pressure governor may assume complete control of the governor mechanism during pressure changes in the elastic-fluid supply.

In witness whereof I have hereunto set my hand this fifteenth day of April, 1921.

REGINALD FRANCIS HALLIWELL.
